UNITED STATES PATENT OFFICE.

PETER FRASER, OF GERMISTON, TRANSVAAL.

STEAM-TRAP.

SPECIFICATION forming part of Letters Patent No. 768,595, dated August 30, 1904.

Application filed June 7, 1904. Serial No. 211,533. (No model.)

To all whom it may concern:

Be it known that I, PETER FRASER, a subject of the King of England, residing at Germiston, in the Colony of the Transvaal, have invented certain new and useful Improvements in Steam-Traps, of which the following is a specification.

This invention consists of improvements in steam-traps for collecting and separating water from steam, and it is also applicable for separating liquids from other gaseous fluids.

The apparatus may be employed for accumulating the water of condensation from steam-pipes and for automatically discharging the same, while preventing the escape of the steam, or it may be employed in connection with the air-receivers of air-compressing plant for removing grease, water, or the like.

The apparatus operates equally well with or without pressure. In it the steam does not play on the valve-face, and the valve is kept closed until the requisite volume of water has accumulated to operate the valve, so that cold air is excluded or prevented from getting into the main steam-pipes or air-receiver when the steam is shut off or the air-compressing plant stopped, thus obviating rapid contraction and consequent fracture of the pipes, &c. In the operation of the apparatus nothing but water is ejected when it is under a pressure of steam or air, and the area of the valve-opening may be made of a size suitable for any desired pressure.

The several operative parts of the apparatus are all attached to the cover of the receiver, which simplifies the construction and facilitates access to the same. The movements of the operative parts are very short, so that they are not likely to get out of order, and the valve operating on the principle of the slide-valve, with the pressure of the steam or air on the back of the valve, the action becomes more efficient with use.

The invention will now be described in detail by aid of the accompanying drawings, in which—

Figure 1 represents a longitudinal sectional elevation of the apparatus with the valve closed. Fig. 2 is a similar view illustrating the position the parts assume to open the

valve to open the outlet for the water, and Fig. 3 is an elevation of the spherical weight.

In the construction of the appliance I provide a drum or cylindrical receiver A for the water. This drum A is located at the lowest point in the steam pipe or pipes which it is intended to serve, so that all the water of condensation flows out of the steam-pipes into it. The cylinder or receiver A is, as shown in the drawings, preferably cast in one piece with supports B B', upon which it stands. In the top of the receiver A is provided an inlet b, which may be formed with an internal screw-thread, into which the end of the steam-pipe or a branch pipe from the steam-pipe may be screwed to place the steam pipe or pipes in communication with the interior of the receiver A. One end of the cylinder A is closed, and the other end of the cylinder is fitted with a cover C, which may be bolted to a flange a formed round the open end of the cylinder, or be otherwise attached thereto in any convenient manner.

On the cover C on the inside are formed two lugs c, which support a pin or pivot c'. On the pin c' is pivoted one end of a lever D, which at its outer and free end has attached to it a float E. The float E is preferably of the shape shown or made semispherical in its lower portion and flatter in the upper portion, so as to allow the float E to rise higher in the cylinder to lift the lever D than would be possible were the float E made truly spherical.

On the inside of the cover C beneath the lugs c, supporting the pin c', is formed a rectangular boss or projection F. In the rectangular projection F is formed a vertical hole f, in which is located a valve G. A recess f' is formed in the end or front of the rectangular boss F, exposing the front of the valve G or intersecting the vertical hole f, in which the valve G is arranged.

g is the port or passage forming the outlet for the water through the valve G. It is preferably made flaring or bell-mouthed.

In the boss or projection F is formed an outlet-port f'', which communicates with a hole c'', formed through the front of the cover C. The hole c'' may be formed with a screw-thread c'', into which may be screwed a pipe for car-

rying off the water when it passes through the valve G.

In Fig. 1 the valve G is shown in the position it assumes when the valve is closed, and in Fig. 2 it is shown in its open position. In this latter position the valve-spindle G rests on the inside of the receiver A below the boss F, which insures it being brought into coincidence with the outlet f^2 in the boss F when 10 the lever D is raised by the float E.

At the front of the rectangular projection F is fixed a vertical rod or support H, in the upper extremity of which is pivoted a lever J. One arm, γ , of this lever J projects into 15 a niche or recess g' in the upper end of the valve-spindle G and serves for raising the valve G to close it in the manner hereinafter described. The rod H may be fixed by means of the screw or stud h , which screw or stud h 20 may also serve for fixing a spring h' , provided for keeping the valve G on its seat in the hole f in the projection F. The spring h' rests on a flat surface formed on the front of the valve G.

On the end of the lever D, pivoted to the 25 cover C, is arranged a spherical weight K. This sphere K is formed with an annular groove k round the center, or it has the form of two hemispheres connected by a short cylindrical piece k' at the center. This is fully 30 shown in Fig. 3. The width of the groove k round the sphere K is slightly greater than the thickness of the lever D, so that when it is placed on the lever the hemispheres project to either side of the lever D and serve to keep 35 it in its position thereon. The lever D is formed with two horns or projections d d' and with a straight edge d^2 , leading into a recess d^3 . The spherical weight K works backward and forward between the horns or projections 40 d d' . In Fig. 1 it is shown in the position it assumes when the float E is at the bottom of the receiver A. In this position it is in engagement with the outer arm γ' of the lever J and out of engagement with the upper end 45 of the valve-spindle G. The cylindrical connecting-piece k' between the hemispheres then takes up a position in the curve formed by the inside of the horn or projection d . As the water accumulates the float E rises and 50 raises the outer end of the lever D. When it has raised the lever D sufficiently far to incline the straight edge d^2 in the direction of the pivot c' , the sphere K then rolls down the inclined edge on the cylindrical piece k' and 55 drops into the recess d^3 . As it drops into the recess it engages the top of the valve-spindle G and depresses it, and so opens the port g in the valve G to the port f^2 in the rectangular boss F, communicating with the water-outlet 60 c^2 . In its lowest and open position the bottom of the valve G rests on the bottom of the cylinder A beneath the rectangular projection F. The several parts remain in this position, and the water continues to pass out of the cylinder A through the valve G until the water- 65

level falls sufficiently to permit the sphere or weight K to roll down the straight edge d^2 , which will now be inclined in a downward direction from the recess d^3 . The horn d' is curved inward, and as the float E, and with it 70 the lever D, falls the sphere K is supported by the valve-spindle G in the recess d^3 until the curved edge of the horn d' pushes it forward onto the straight edge d^2 , down which it rolls into the recess formed by the front horn or 75 projection d . As it rolls down the straight edge the weight K engages the other arm, γ' , of the lever J, which lever J thereupon raises the valve G, and so closes the outlet c^2 for the water. 80

What I claim as my invention, and desire to protect by Letters Patent, is—

1. In a steam-trap or means for separating liquids from gaseous fluids in combination, a receptacle into which the steam or gaseous fluid is admitted and in which the water accumulates, a lever pivoted at one extremity in said receiver and carrying a float at the other end, a valve controlling an outlet-port for the water, and a weight mounted on the lever operating to open said valve when the float and lever rise and to rest on said valve so as to close it when the float and lever fall, substantially as described. 90

2. In a steam-trap or means for separating liquids from gaseous fluids in combination, a receptacle into which the steam or gaseous fluid is admitted and in which the water is collected, a lever pivoted at one extremity in said receiver and formed with a recess and a straight edge communicating with said recess at or in proximity to the pivoted extremity thereof, a float fixed at the outer end of the lever, a valve controlling an outlet-port for the water, a weight mounted on the lever and adapted when the float raises the lever to roll down the straight edge into the recess and engage the valve-spindle to open the valve, and when the float and lever fall to roll out of the recess down the straight edge and operate 100 means for closing the valve, substantially as described. 105

3. In a steam-trap or means for separating liquids from gaseous fluids in combination, a receptacle or receiver into which the steam or gaseous fluid is admitted and in which the water accumulates, a cover for said receptacle, a lever pivoted at one extremity to said cover and formed with two horns or projections and a recess and straight edge between 115 said projections, a float fixed to the other end of said lever, a valve attached to the cover and controlling an outlet formed through the cover for the water, a weight mounted on the lever and adapted when the float raises the 120 lever to roll down the straight edge into the recess and engage the valve-spindle to open the valve and when the float and lever fall to be supported by the valve-spindle and be thrown onto the straight edge between the projec- 125 130

tions to roll into engagement with the other projection, a lever engaging the valve-spindle which is operated by the weight when it rolls down the straight edge to raise the valve-spindle and close the valve, substantially as described.

4. In a steam-trap or means for separating liquids from gaseous fluids in combination, a receptacle provided with an inlet at the top

- 10 for the steam or gaseous fluid, into which receiver the water drains and collects, a lever pivoted at one extremity in said receiver, a float fixed at the other end of the lever, an outlet for the water at the base of the receiver, a valve located in the receiver beneath the pivoted end of the lever and adapted to be operated to open or close the water-outlet to the interior of the receiver and arranged so that the lower extremity of the valve engages
- 15 the bottom of the receiver when the valve is fully open, means for keeping the valve on its seat or over the water-outlet in the receiver, a weight adapted to roll longitudinally of the lever within certain limits and to engage the top of the valve to depress the same when the lever is raised and to raise the valve to close the port when the lever falls, substantially as described.
- 20
- 25

- 5. In a steam-trap or means for separating liquids from gaseous fluids in combination, a cylindrical receiver open at one end, an aperture formed in the top thereof through which the steam or gaseous fluid and water or liquid are admitted, a cover fitted to the open end 30 of said cylinder formed with lugs on the inside thereof and with a boss or projection in proximity to the bottom of the receiver through which boss an outlet is formed for the water draining into the receiver, a lever 35 pivoted to the lugs formed on the cover, formed with two curved horns or projections and a recess and straight edge between said horns or projections, a weight, comprising two hemispheres joined by a central cylindrical piece,
- 40 mounted on the lever and adapted to roll between the horns on the cylindrical connecting-piece, a valve arranged in the boss on the cover projecting to the under side of the lever and adapted to be engaged by and depressed when
- 45

the weight rolls down the straight edge and falls 50 into the recess in the lever to open the valve in such manner that when the lever falls the weight is supported by the valve-spindle and raised out of the recess onto the straight edge, and means operated by the weight which raise 55 the valve to close the port when the lever and float fall in the receiver, substantially as described.

6. In a steam-trap or means for separating liquids from gaseous fluids in combination, 60 the receiver A having the aperture b through which the steam or gaseous fluid and water or liquid enter the receiver, the legs B B' connected to said receiver and the flange a formed round the open end thereof, the cover C fixed 65 to the flange a on the receiver, having the lugs c on the inside thereof and the boss F secured to said cover in proximity to the bottom of the receiver, said boss having the outlet f² for the water and the recess f' in the 70 front thereof, the pin c' carried by the lugs c, the lever D pivoted on the pin c' and having the horns or projections d d', said lever also having the recess d² therein and the straight edge d² thereon, the float E on the outer end 75 of the lever D, the weight K comprising the two hemispheres and the cylindrical connecting-piece k' joining the hemispheres together and adapted to roll on the lever D between the horns d d', the valve G having the port g 80 formed therein for opening and closing the outlet f² in the boss F, the spring h' located in the recess f' engaging the valve G at the front to keep it on its seat, the rod H fixed to the boss F, the valve-lever J pivoted in the 85 upper end of the rod H engaging the upper end of the valve G and operating to raise the valve to close the water-outlet f² when the weight rolls down the straight edge d² out of the recess d² substantially as described. 90

In witness whereof I have hereunto set my hand in the presence of two subscribing witnesses.

PETER FRASER.
